(57) **CLAIM**

The ornamental design for a reclosable storage bag, as shown and described.

DESCRIPTION

FIG. 1 is a top front perspective view of the reclosable storage bag in an open configuration showing our new design;

FIG. 2 is a front view thereof;

FIG. 3 is a rear view thereof;

FIG. 4 is left side view thereof;

FIG. 5 is a right side view thereof;

FIG. 6 is a top view thereof; and,

FIG. 7 is a bottom view thereof.

The broken lines show portions of the reclosable bag that form no part of the claimed design. The dot-dash lines show no specific length and form no part of the claimed design. For ease of illustration, the dot-dash broken lines do not appear in FIG. 1. The shade lines in the Figures indicate a transparent or translucent surface.
